UNITED STATES PATENT OFFICE.

GEORGE DECHEFF, OF DETROIT, MICHIGAN.

SAW-FILING MACHINE.

Application filed January 31, 1925. Serial No. 6,113.

To all whom it may concern:

Be it known that I, GEORGE DECHEFF, a citizen of the United States, residing at Detroit, in the county of Wayne and State of Michigan, have invented certain new and useful Improvements in Saw-Filing Machines, of which the following is a specification, reference being had to the accompanying drawings.

10 This invention relates to improvements in saw filing machines and it is an object of the invention to provide a device of this kind embodying novel and improved means whereby the saw may be effectively held or clamped in desired position.

Another object of the invention is to provide a novel and improved device of this general character which may be adjusted in a manner whereby the file or the like may 20 be adjusted in a direction substantially the same as the line of the toothed edge of the saw blade.

The invention also has for an object to provide a novel and improved device of 25 this kind including a holding or clamping structure together with a carrier slidably supported by said structure, the carrier being adapted to support a saw file or other implement, together with means for adjusting the carrier in accordance with the spacing or size of the teeth of the saw to be operated upon.

The invention consists in the details of construction and in the combination and 35 arrangement of the several parts of my improved saw filing machine whereby certain important advantages are attained and the device rendered simpler, less expensive and otherwise more convenient and advantageous 40 for use, as will be hereinafter more fully set forth.

The novel features of my invention will hereinafter be definitely claimed.

In order that my invention may be the 45 better understood, I will now proceed to describe the same with reference to the accompanying drawings, wherein:—

Figure 1 is a view in top plan illustrating a saw filing machine constructed in accordance with an embodiment of my invention with portions broken away;

Figure 2 is a view in front elevation of the structure as illustrated in Figure 1;

Figure 3 is a view in perspective of the elongated member or bar attached to the 55 base as herein set forth;

Figure 4 is a view in perspective of one of the saw gauges as herein employed;

Figure 5 is a sectional view taken substantially on the line 5—5 of Figure 1; 60

Figure 6 is a view in perspective of one of the end supporting members or brackets;

Figure 7 is a fragmentary sectional view taken longitudinally of the base as herein employed and illustrating in part the means 65 for flexing or bending such base;

Figure 8 is a sectional view taken substantially on the line 8—8 of Figure 1;

Figure 9 is a fragmentary view in elevation illustrating the use of a saw set. 70

As disclosed in the accompanying drawings, 1 denotes a base preferably of wood, and said base being relatively long and provided at its opposite ends with the upstanding plates or brackets 2. An elongated rod 75 3 has its end portions disposed through the upper portions of the brackets 2, each of said brackets being provided with an opening 4 to receive an end portion of the rod 3. The rod 3 is effectively maintained in applied 80 position through the medium of a binding screw 5 threaded from above through one of the brackets 2 and having requisite contact with the adjacent inserted end portion of the rod 3. The rod 3 has disposed 85 therealong a plurality of circumferentially spaced series of notches 6. The notches of each series being spaced in a direction lengthwise of the rod 3 and each series of notches is differently spaced than the 90 notches of the other series. The notches of each series are spaced in accordance with the given size or point of the teeth of a saw for a purpose which will hereinafter be more particularly referred to. 95

Resting upon the upper surface of the base 1 and extending along a longitudinal marginal portion thereof is a metallic member or strap 7 provided at its opposite end portions with the depending flanges 8. The member or strap 7 may be held in applied 100 position in any desired manner but as here-

in disclosed, the opposite end portions thereof have disposed therethrough the holding screws 9 engaging the base 1. Overlying the forward edge of the base 1 and the flanges 8 of the member or strap 3 is an elongated clamping bar 10 through the opposite end portions of which are directed the clamping bolts 11 in threaded engagement with the flanges 8. It is to be noted that one of the flanges 8 is provided with a plurality of threaded openings 12 with which a clamping bolt 11 is adapted to be selectively engaged in accordance with the size of the saw to be filed, reset or the like.

15 Each of the clamping bolts 11 has slidably disposed through the head thereof an operating handle 14 to facilitate effective manipulation of the clamping bolt.

In practice, the saw to be filed or the like 20 has its toothed marginal portion inserted between the forward edge of the base 1 and the bar 10 with the teeth upwardly disposed. In order to assure the proper placing of the saw, the gauges 15 are arranged adjacent the 25 opposite ends of the member or strap 7, each of said gauges being pivotally held to the member or strap 7 by a screw 16. When each of the gauges 15 is disposed in a direction lengthwise of the member or strap 7, 30 the same is provided with a laterally directed lug 17 which is adapted to be received between a pair of adjacent teeth of the saw and thereby assure the requisite and desired placing of the saw. After the saw has been 35 properly placed and clamped by the bar 10, the gauges 15 are sprung inwardly into an inoperative position.

It is to be noted that one end portion of the member or strap 7 is provided with a 40 series of spaced threaded openings 18 with which the holding screw 16 of one of the gauges 15 is adapted to be selectively engaged so that such gauge may be adjusted with respect to the member or strap 7 in 45 accordance with the size of the saw. The bar 10 is constantly urged or forced outwardly by the coil springs 19 interposed between the opposite end portions of the base 1 and the bar 10. These springs 19 are of 50 such tension that when the clamping bolts 11 are retracted to effect a release of an applied saw, the bar 10 may be automatically forced outwardly to facilitate such removal of the saw.

55 Mounted on the opposite end portions of the bar 10 outwardly of each of the bolts 11 and inwardly of the adjacent spring 19 is a cuff or sleeve 20, the inner or interposed wall of which being of a thickness substantially 60 equal to the thickness of the saw blade. By use of these sleeves or cuffs outbowing of the central portion of the bar 10 is avoided when the clamping bolts 11 are tightened and thereby assuring a close contact of the 65 bar 10 at all points along the saw to effec-

tively maintain the saw in applied position and to hold the same against rattling or vibration when being operated upon by a file or the like. As the position of a clamping bolt 11 is adjusted lengthwise of its flange 70 8 and the bar 10 it is to be understood that the adjacent cuff or sleeve 20 is correspondingly adjusted in order to maintain a maximum of efficiency.

The base 1, as herein disclosed, is provided adjacent its opposite ends with the clamps 21 of a well known type whereby said base may be effectively held to a workbench or the like.

As is well known, the toothed edges of new saws are generally disposed on a slight outward curvature and in order to maintain such curvature when filing a saw it is of importance that the intermediate portion of the base 1 be sprung upwardly to an extent 85 substantially equal to such curvature of the toothed edge of the saw. As herein disclosed, the base 1 adjacent the forward longitudinal marginal portion thereof is provided with a longitudinally directed groove or 90 channel 22 in which is arranged an elongated metallic strap 23 the extremities of which being slidably engaged, as at 24, with the headed holding members 25. Normally the strap 23 is entirely housed or confined 95 within the groove or channel 22 so that no hindrance or obstruction is offered to the under surface of the base 1. However, when it is desired to spring upwardly the intermediate portion of the base 1, the central 100 part of the strap 23 is forced outwardly to the extent desired. In the present embodiment of my invention this is accomplished 105 through the medium of the elongated screw 26 threaded inwardly from the rear through the base 1, the inserted end portion of the screw 26 being tapered, as at 27, for contact with the inclined wall 28 provided on the inner face of the strap 23 and at preferably 110 the longitudinal center thereof. As the screw 26 is forced inwardly, the central portion of the strap 23 will be moved outwardly and as the bolt or screw 26 is retracted, the inherent resiliency of the strap 23 will cause 115 the same to return inwardly of the channel 22.

Freely mounted on the rod 3 is a carrier C with which is adapted to be attached a file holder H or a saw set S. As herein disclosed, the carrier C comprises a barrel 29 snugly surrounding the rod 3 and to which is connected a plate 30 extending beyond opposite sides of the barrel 29. The base block 31 of the saw holder, as herein disclosed, has one end portion pivotally connected, as at 32, to the inner or rear end portion of the plate 30 while the forward portion of said block has engaged therewith a holding screw 33 disposed through an ar- 120 cuate slot 34 in the forward end portion of 125 130

the plate 30 so that the holder H in its entirety may be adjusted at desired angle with respect to the saw as the requirements of practice may necessitate.

5 A detailed description of the file holder is not believed to be necessary as the same is fully described and illustrated in another application for patent executed on even date herewith.

10 The saw set S is substantially of a type now generally in use and is attached only to the forward or front end portion of the plate 30, said attached portion of the set being provided with a lug 35 which extends within 15 in a notch 36 in the forward end marginal portion of the plate 30 whereby said set is held against lateral or side movement.

As herein disclosed, the barrel 29 is provided with a latch mechanism 37 which is 20 adapted to engage within a notch 6 so that the carrier C is maintained in a fixed position during the period the file holder H or the saw set S is in use. After one tooth has been operated upon it will be understood 25 that the carrier C will be adjusted along the rod 3 to the next notch and as the notches in each series are spaced in accordance with a given size or point it will be readily noted that the efficiency of the device is materially increased. When a saw 30 is applied, the rod 3 is rotated to dispose forwardly the proper series of notches 6.

From the foregoing description it is 35 thought to be obvious that a saw filing machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as 40 limiting myself to the precise arrangement and formation of the several parts herein shown in carrying out my invention in practice except as hereinafter claimed.

I claim:

50 1. An apparatus of the class described comprising, in combination, a base, means coacting with the base for clamping a saw thereto, means for supporting a tool by the base, attaching means carried by the extremities of the base, and means operating to elevate the central portion of the base.

55 2. An apparatus of the class described comprising, in combination, a base, means coacting with the base for clamping a saw thereto, means for supporting a tool by the base, attaching means carried by the extremities of the base, a resilient strap underlying the base, means for holding the same to the base, and means for forcing the central portion of the strap outwardly from the base.

3. An apparatus of the class described comprising, in combination, a base, means coacting with the base for clamping a saw thereto, means for supporting a tool by the base, attaching means carried by the extremities of the base, a resilient strap underlying the base, means for holding the same to the base, and means for forcing the central portion of the strap outwardly from the base, said under face of the base being provided with a groove in which the strap is normally housed. 70

4. An apparatus of the class described comprising, in combination, a base, means coacting with the base for clamping a saw thereto, means for supporting a tool by the base, attaching means carried by the extremities of the base, a resilient strap underlying the base, means for holding the same to the base, the central portion of the strap being provided with an inclined surface, and a member movable through the base and contacting with said inclined surface to force the central portion of the strap outwardly of the base. 75 80

5. An apparatus of the class described comprising, in combination, a base, an elongated member resting upon the upper surface of the base and extending along a longitudinal marginal portion thereof, said member being provided at its opposite end portions with depending flanges, a clamping bar extending along the adjacent edge of the base and overlying the flanges of the member, clamping screws disposed through the end portion of the clamping bar and in threaded engagement with the flanges, and means for supporting a tool for engagement with a saw clamped between the bar and base. 85 90 95

6. An apparatus of the class described comprising, in combination, a base, an elongated member resting upon the upper surface of the base and extending along a longitudinal marginal portion thereof, said member being provided at its opposite end portions with depending flanges, a clamping bar extending along the adjacent edge of the base and overlying the flanges of the member, clamping screws disposed through the end portions of the clamping bar and in threaded engagement with the flanges, means for supporting a tool for engagement with a saw clamped between the bar and base, and cuffs mounted upon the bar outwardly of the clamping screws for contact with the base when the bar is in clamping action. 100 110 115

7. An apparatus of the class described comprising, in combination, a base, an elongated member resting upon the upper surface of the base and extending along a longitudinal marginal portion thereof, said member being provided at its opposite end portions with depending flanges, a clamping bar extending along the adjacent edges of 120 125 130

the base and overlying the flanges of the member, clamping screws disposed through the end portions of the clamping bar and in threaded engagement with the flanges 5 of the member, means for supporting a tool for engagement with a saw clamped between the bar and base, and expansible members

interposed between the bar outwardly of the clamping screws and the base to urge the bar outwardly.

10

In testimony whereof I hereunto affix my signature.

GEORGE DECHEFF.
